(57) **CLAIM**

We claim the ornamental design for a personal mobility vehicle lift, as shown and described.

DESCRIPTION

FIG. 1 is a front right perspective view of a personal mobility vehicle lift showing our new design.

FIG. 2 is a right side elevation thereof;

FIG. 3 is a front elevation thereof;

FIG. 4 is a top plan view thereof;

FIG. 5 is a left front perspective view thereof;

FIG. 6 is a rear elevation view thereof;

FIG. 7 is a right rear perspective view thereof;

FIG. 8 is a left rear perspective thereof; and,

FIG. 9 is a left side elevation thereof.
